CLAIM

The ornamental design for a tire for road vehicles, as shown and described.

DESCRIPTION

FIG. 1 is a perspective view of a tire for road vehicles embodying our design, it being understood that the tread pattern is repeated throughout the circumference of the tire, as shown schematically by solid lines, the opposite side being substantially the same as that shown. FIG. 2 is an enlarged fragmentary front elevational view thereof. FIG. 3 is an enlarged fragmentary side elevational view thereof.

FIG. 1

FIG. 2

FIG. 3
